[57] **CLAIM**

The ornamental design for a combined cap and adapter ring for a fuel tank, as shown.

DESCRIPTION

FIG. 1 is a top plan view of a combined cap and adapter ring for a fuel tank showing my new design; FIG. 2 is another top plan view thereof, showing the handle in an open position;

FIG. 3 is a right side elevational view of FIG. 1;

FIG. 4 is a right side elevational view of FIG. 2;

FIG. 5 is a front elevational view of FIG. 1;

FIG. 6 is a front elevational view of FIG. 2;

FIG. 7 is a left side elevational view of FIG. 1;

FIG. 8 is a left side elevational view of FIG. 2;

FIG. 9 is a rear elevational view of FIG. 1;

FIG. 10 is a rear elevational view of FIG. 2;

FIG. 11 is a bottom plan view thereof;

FIG. 12 is a fragmentary cross sectional view taken on line 12—12 of FIG. 11;

FIG. 13 is a top plan view of the cap portion thereof; FIG. 14 is another top plan view of the cap portion thereof, showing the handle in an open position;

FIG. 15 is a right side elevational view of FIG. 13;

FIG. 16 is a right side elevational view of FIG. 14;

FIG. 17 is a front elevational view of FIG. 13;

FIG. 18 is a front elevational view of FIG. 14;

FIG. 19 is a left side elevational view of FIG. 13;

FIG. 20 is a left side elevational view of FIG. 14;

FIG. 21 is a rear elevational view of FIG. 13;

FIG. 22 is a rear elevational view of FIG. 14;

FIG. 23 is a bottom plan view of FIG. 13;

FIG. 24 is a top plan view of the adaptor ring portion thereof;

FIG. 25 is a right side elevational view of FIG. 24;

FIG. 26 is a front elevational view of FIG. 24;

FIG. 27 is a left side elevational view of FIG. 24;

FIG. 28 is a rear elevational view of FIG. 24; and

FIG. 29 is a bottom plan view of FIG. 24.
